UNITED STATES PATENT OFFICE.

PETER H. RAUN, OF FREDERICK, MARYLAND, ASSIGNOR TO THE FREDERICK IRON & STEEL COMPANY, OF FREDERICK, MARYLAND, A CORPORATION OF MARYLAND.

CLASSIFYING OR SEPARATING MACHINE.

Application filed January 7, 1926. Serial No. 79,745.

My invention relates broadly to classifying or separating machines and more particularly to the construction of a machine for separating material into predetermined sizes with means for preventing clogging of the material during the separating process.

One of the objects of my invention is to provide a construction of classifying machine in which a plurality of longitudinally disposed rollers are provided with means for spraying liquid from the rollers for preventing clogging of material between the rollers.

Another object of my invention is to provide a construction of classifying machine in which a plurality of longitudinally disposed rollers spaced one from another throughout their length are provided, with liquid spray means for preventing clogging of material between the rollers and enabling the machine to be operated while the material which is being classified is in moist condition for avoiding undesirable distribution of dust particles and dirt in the vicinity of the machine.

Still another object of my invention is to provide a construction of combined manifold and bearings for a plurality of hollow rollers in a separating or classifying machine, the manifold connecting the rollers with a source of fluid pressure and the rollers being apertured to enable the fluid to be sprayed upon the material which is being classified.

A further object of my invention is to provide a construction of classifying machine in which the material being separated is passed over a plurality of longitudinally spaced rollers and subjected to a liquid spray both upwardly and downwardly for maintaining the material in moist condition and preventing clogging between the rollers while material of a predetermined size passes through the rollers and oversize material is conveyed over the rollers and discharged therefrom.

My invention will be more fully understood from the following specification by reference to the accompanying drawings, wherein:

Figure 1 is a plan view illustrating the arrangement of longitudinally spaced rollers and the liquid spraying apparatus by which the material is treated during the classifying operation; Fig. 2 is a longitudinal view partially in cross-section through the classi-

fying machine on line 2—2 of Fig. 1; and Fig. 3 is a lateral cross-sectional view of the machine on line 3—3 of Fig. 2.

Referring to the drawings in more detail, the separating or classifying machine is driven from a main shaft 1 having a pulley 2, thereon which may be driven by belt 3. A gear case 4 is provided in which the shaft 1 is housed enclosing bevel gears 5 and 6 keyed to the shaft 1 in positions where the gears mesh with bevel pinion gears represented at 7 and 8 on the end of the rotatable shafts 9 and 10. There are a plurality of similar shafts in the classifying machine which I have represented at 11, 12, 13, and 14. The shafts 11, 12, 9, 10, 13 and 14 are journaled in bearing members 15, 16, 17, 18, 19 and 20 which are adjustably mounted on a lateral end frame member 21 in such manner that the spaces between the bearing members may be selected in proportion to the size of material which it is desired to pass through the classifying machine. The classifying machine is built up by a structure comprising the laterally extending frame members 21 and 22 connected by means of longitudinally extending side frame members 24 and 25. Positioned within the longitudinally extending frame members 24 and 25 and between the laterally extending frame members 21 and 22 I provide a plurality of rollers 26, 27, 28, 29, 30 and 31 supported on the shaft members 11, 12, 9, 10, 13 and 14 at one end and on hollow shaft members 32, 33, 34, 35, 36, and 37 on the opposite ends thereof. Adjustable bearing members 38, 39, 40, 41, 42 and 43 are carried by the laterally extending frame member 22 and form journals for the lower ends of the rollers in a manner similar to the journals 15, 16, 17, 18, 19 and 20 carried in the upper frame member 21. The rollers are mounted in an inclined plane enabling material to be passed thereover and gravitated toward the lower end of the machine. The lower ends of the rollers are each provided with baffle plates as has been represented in the case of roller 29 by baffle plate 44 and the lower ends of the rollers are each perforated with apertures designated at 26^a, 27^a, 28^a, 29^a, 30^a and 31^a.

Liquid under pressure is conveyed to each of the perforated sections through a manifold 45 with tube members 46, 47, 48, 49, 50 and 51 extending through each of the bearings 38, 39, 40, 41, 42 and 43 and passing into 105 110

the hollow perforated portions of the rollers. The tube members provide means for leading the fluid under pressure within the hollow rollers at the same time that they serve as journals for the lower ends of the rollers. I provide a pair of guide plates 52 and 53 for directing the material which is deposited in the classifying machine over the longitudinally extending rollers. Above the guide plates 52 and 53 adjacent the lower end of the classifying machine, I provide a laterally extending manifold 54 through which liquid under pressure is conveyed and sprayed through apertures 54^a upon the material being passed through the classifying machine. Beneath the manifold 54 and the apertured portions in the rollers 26, 27, 28, 29, 30 and 31 I provide a trough 55 in which the excess liquid which is not absorbed by the material passing through the classifying machine is caught and conveyed away through a pipe line 56.

In the operation of the classifying machine, the rollers 26, 27, 28, 29, 30 and 31 are spaced at predetermined positions with respect to each other by fixing the adjustable bearings 15, 16, 17, 18, 19 and 20 at the upper end of the rollers and the adjustable bearings 38, 39, 40, 41, 42 and 43 at the lower ends of the rollers at predetermined distances in the lateral frame members 21 and 22. The material which is then deposited upon chute 57 and against guide plates 52 and 53 is conveyed in an inclined direction over the driven rollers and material of a predetermined size passes through the rollers while oversize material is discharged over the rollers at the lower end of the classifying machine, while the material is treated by liquid spray under pressure in opposite directions.

While I have described my invention in certain particular embodiments, I desire that it be understood that modifications may be made and that no limitations upon the invention are intended other than those imposed by the scope of the appended claims.

What I claim and desire to secure by Letters Patent of the United States is as follows:

1. A separating or classifying machine comprising in combination a plurality of rollers spaced one from another in an inclined plane, means for delivering material to be separated over said rollers, sets of bearings for opposite ends of said rollers, sections of said rollers being apertured, said bearings adjacent said sections being provided with means for conveying fluid under pressure to said sections for subjecting the material to be separated to liquid sprays emanating from said rollers.

2. A separating or classifying machine comprising in combination a plurality of apertured rollers spaced one from another

in an inclined plane, and means mounted adjacent the lower end of said rollers and concentric with the axes thereof for conveying liquid under pressure to said rollers for subjecting material which is to be classified to a liquid spray emanating from said rollers. 70

3. A separating or classifying machine comprising in combination a plurality of rollers spaced one from another and mounted in an inclined plane, means for directing bulk material to be separated over said rollers, bearings for opposite ends of said rollers, the lower portions of each of said rollers being apertured, and means extending through the bearings at the lower ends of said rollers for introducing liquid under pressure into the apertured portions of said rollers whereby the material which is to be separated is subjected to liquid spray emanating from said rollers. 80 85

4. A separating or classifying machine comprising in combination a plurality of rollers spaced one from another and mounted in an inclined plane, means for directing bulk material to be separated over said rollers, bearings for opposite ends of said rollers, the lower portions of each of said rollers being apertured, means extending through the lower bearings into said rollers for introducing liquid under pressure into said apertured portions of said rollers, and means above said apertured portions of said rollers for directing a spray of liquid downwardly to meet the spray of liquid directed from said rollers, whereby material 90 95 to be separated is passed through opposed liquid sprays. 100

5. A separating or classifying machine comprising in combination a plurality of longitudinally extending rollers spaced one from another, means for directing bulk material to be separated over said rollers, separate upper and lower sets of bearings for opposite ends of said rollers, a manifold adjacent the lower set of said bearings, the lower ends of said rollers being hollow and arranged to receive fluid under pressure from said manifold, said rollers being apertured to permit liquid to be sprayed upon material being passed over said rollers for separation. 110 115

6. In a separating or classifying machine the combination of a plurality of longitudinally extending rollers, sets of upper and lower bearings for said rollers, the set of lower bearings being apertured for the passage of pipe members therethrough, the lower ends of each of said rollers being hollow to receive liquid under pressure therein and apertured to permit the spraying of fluid therefrom over a limited portion of the length of said rollers, the external ends of said pipe members being supplied from a common manifold with fluid under pressure, whereby material being sep- 120 125 130

arated is subjected to a liquid spray during the separating process.

7. A separating or classifying machine comprising in combination a plurality of 5 rollers spaced one from another, means for delivering bulk material to be separated over said rollers whereby said rollers operate to grade said material with respect to size, sets of bearings for opposite ends of said 10 rollers, portions of said rollers being apertured and the bearings adjacent said portions being provided with means for conveying fluid under pressure to said portions for subjecting the material to be separated to 15 liquid sprays.

8. A separating or classifying machine comprising in combination a plurality of

rollers spaced one from another, means for directing bulk material to be separated over said rollers, bearings for opposite ends of 20 said rollers, the peripheries of each of said rollers adjacent one end being apertured while the peripheries of said rollers over the remaining portion of their lengths are solid, and means extending through the bearings 25 at the lower ends of said rollers for introducing liquid under pressure into the apertured portions of said rollers whereby the material which is to be separated is subjected to liquid spray. 30

In testimony whereof I affix my signature.

PETER H. RAUN.
